MOLD LINER GAUGING DEVICE FOR TYPE CASTING MACHINES

Filed Oct. 8, 1924

Patented Sept. 7, 1926.

UNITED STATES PATENT OFFICE.

THOMAS E. WINDLE, OF FORT WORTH, TEXAS, ASSIGNOR TO WINDLE MANUFACTURING COMPANY, OF FORT WORTH, TEXAS, A CORPORATION OF TEXAS.

MOLD-LINER-GAUGING DEVICE FOR TYPE-CASTING MACHINES.

Application filed October 8, 1924. Serial No. 742,488.

My invention relates to mold liner gauges and more particularly to gauges for setting the liners to determine the number of ems in length to be set; and the object is to provide certain devices for gauging and setting the liners for use on linotype, intertype, linograph, or type setting machines at any required length from four ems to twenty six ems and from four and one-half ems to twenty-six and one-half ems by which a measure of forty-six lines may be made with one liner on single slugs. The same devices are also adapted for use with double slugs. Other objects and advantages will be fully explained in the following description and the invention will be more particularly pointed out in the claims.

Reference is had to the accompanying drawings which form a part of this application.

Fig. 1 is a front elevation of the devices assembled, showing the gauge mounted on the mold. Fig. 2 is a broken view of the adjusting rod for setting the vice jaw to correspond with the length of the line being set. Fig. 3 is a face view of a liner for setting different lengths of slugs which takes the place of forty-six different liners, ranging from four ems to twenty-six ems and from four and one-half ems to twenty-six and one-half ems because this liner can be held in place by the clamp at any measure required as indicated by the gauge. Fig. 4 is a face view of a recessed liner for recessed molds and ranges from ten points to thirty-six points. Fig. 5 is a broken sectional view, illustrating a variation of the end spring which holds the gauge on the mold. Fig. 6 is a transverse section of the gauge, taken on the line 6—6 of Fig. 1, showing the relative positions of gauge and mold. Fig. 7 is a plan view of the sliding box and gauge. Fig. 8 is a face view of the mold and a broken view of the mold disk. Fig. 9 is a plan view of the liner clamp. Fig. 10 is an inverted plan view of the adjuster.

Similar characters of reference are used to indicate the same parts throughout the several views.

The improved liner and gauge herein set forth avoids the necessity of buying a great variety of liners of different lengths. In the present practice, a liner must be bought for each different measure. With the im-

proved liner, forty six different measures may be had with one liner and with twelve liners with forty six measures to each liner, 552 measures may be set. To buy liners for the 552 measures, at present way or 60 practice, the cost would be \$1,656.00. The improved liner and gauge will eliminate approximately 75 per cent of the expense in buying liners, avoids the loss of time in sawing metal, avoids the waste of metal by 65 sawing, and avoids much other expense and loss of time in operation.

The drawings show a mold for ordinary type and the improvements mounted thereon. A frame for the improvements consists of two bars or rails 1 and 2 and blocks or end members 3 and 4, these blocks or end members having cut-outs, as shown in Fig. 7, to receive the ends of the bars 1 and 2 which may be attached thereto by countersunk screws or otherwise. A slideable box or carrier 5 is mounted on the lower rail 2 and is held in place thereon by the upper rail 1, the end of the carrier projecting between the two rails. The rail 2 has a longitudinal groove in its upper surface near the rear edge and a tongue 6 depending from the underside of the carrier or box 5 runs in this groove in the lateral movements of the carrier or box. The lower rail 2 has 80 depending lugs 7 and 8 which project into a groove 9 in the mold 10. The gauge frame is thus held securely against vertical movement. The gauge frame is further braced and secured in place by the spring clamps 90 11 and 12 which are attached to the end members 3 and 4 and press against the ends of the mold 10. The gauge frame has a gauge 13 which projects into the mold 95 groove 14. The gauge 13 serves as a base or starting point for taking the measurements.

The carrier frame is to be temporarily placed on the mold for positioning the liner in the molding groove in the mold. The 100 carrier 5 is slidably mounted in the space between the rails or bars 1 and 2 and is movable in either direction. The carrier is substantially a U-shaped open topped frame for receiving and holding the liner 105 adjuster. See Figs. 1 and 9. The carrier 5 has grooves 15 in the lowest parts of its side walls to receive the lateral flanges 16 of the adjuster 17. The adjuster 17 is held against vertical movement by the flanges 110

16 projecting in the grooves of the carrier 5. As a further means of fitting the carrier 5 and the adjuster 17 together, the carrier 5 has a groove in the central part of the upper surface of the bottom and the adjuster 17 has a tongue 18 which runs in this groove, thus aligning the adjuster 17 and carrier 5 together for inward and outward movement of the adjuster. This tongue will bank the adjuster against the mold. The wall of the adjuster 17 is thick enough to bank against the mold cap 19. The adjuster 17 has one fixed arm 20 and an adjustable arm 21 for clamping the liner which is to be positioned in the mold. The adjuster has a groove 22 in its under face and the arm 21 is integral with a slide 23 which moves in the groove 22. The adjuster 17 has a slot 24 which extends through the adjuster to the groove 22. A spring 25 acts on the movable arm 21 to clamp the liner against the arm 20. The spring 25 seats against the wall of the slot 24 and against a seat 26 which is attached to the slide 23. The slide 23 and the arm 21 are moved against the tension of the spring 25 by a thumb lever 27 which is fulcrumed on the adjuster 17 and projects between a stud 28 (which is rigid with the slide 23) and the seat 26. A finger rest 29 is rigid with the adjuster 17 for convenience in actuating the thumb lever 27 with the thumb. When the arms 20 and 21 are opened by pressing on the lever 27, the arms will receive either one of the liners shown in Figs. 3 and 4.

The upper frame member 1 of the mold has a graduated and numbered pica scale 30 and a notched scale plate 31. The liner is positioned according to these two scales. After the liner (which is carried by the adjuster 17) has been placed in the mold, the mold cap is clamped down on the mold and the gauge is removed. The mold is now ready for casting a slug of the required length.

The carrier 5 is provided with a pointer 32 that comes directly over the pica scale, and when the carrier is moved in any direction to the line to be set, this pointer 32 points to the figure or digit required, and to the right of this pointer 32 there is a thumb latch 33 that is to be pushed into the notch in the scale plate opposite the point for locking the box or carrier and holding it in this position until the liner is placed and the mold cap screwed down.

What I claim is:—

1. Mold liner gauging devices comprising a frame attached to type casting molds provided with a scale and a rack thereon, a carrier mounted on said frame and slidably laterally thereon, a liner clamp, and an adjuster slidably mounted on said carrier for positioning liners in said mold.

2. Mold liner gauging devices comprising

a frame attached to type casting molds provided with a scale and a rack thereon, a carrier mounted on said frame and slidably laterally thereon, a liner clamp, and an adjuster slidably mounted on said carrier for 70 positioning liners in said mold and provided with a pointer for selecting the position relative to said scale.

3. Mold liner gauging devices comprising a frame attached to type casting molds provided with a scale, a rack thereon, a carrier mounted on said frame, and a liner clamp, and an adjuster mounted on said carrier and slidably transversely relative to said carrier for positioning liners in said mold 80 and provided with a latch adapted to engage said rack for holding the liner in the mold until the liner is secured in the mold.

4. Mold liner gauging devices comprising a frame attached to type casting molds provided with a scale and a rack thereon, a carrier mounted on said frame, a liner clamp, an adjuster mounted on said carrier and carrying said clamp for positioning liners in said mold and provided with a pointer 90 for selecting the position relative to said scale and provided with a latch adapted to engage said rack for holding the liner in the mold until the liner is secured in the mold.

5. Mold liner gauging devices comprising a frame attached to type casting molds provided with a scale and a rack thereon, a carrier slidably mounted on said frame, a liner clamp, and an adjuster mounted on 100 said carrier and carrying said clamp for positioning liners in said mold and provided with one stationary member and one movable member.

6. Mold liner gauging devices comprising a frame attached to type casting molds provided with a scale and a rack thereon, a carrier slidably mounted on said frame, a liner clamp, and an adjuster slidably mounted on 110 said carrier and carrying said clamp mounted on said carrier for positioning liners in said mold and provided with one stationary member and one movable member and provided with a lever for actuating said movable member.

7. Mold liner gauging devices comprising a frame attached to type casting molds provided with a scale and a rack member, a carrier slidably mounted on said frame, a liner clamp, said carrier having guideways 120 therein, and an adjuster slidably mounted on said carrier and carrying said clamp and provided with flanges running in said guideways.

8. Mold liner gauging devices comprising 125 a frame attached to type casting molds provided with a scale and a rack thereon, a carrier slidably mounted on said frame, a liner clamp for positioning liners in said mold and provided with one stationary member 130

and a spring controlled movable member and an adjuster slidably mounted on said carrier and carrying said clamp.

9. Mold liner gauging devices comprising
5 a frame attached to type casting molds provided with a scale and a rack thereon, a carrier slidably mounted on said frame, a liner clamp for positioning liners in said mold and

provided with one stationary member and a spring controlled movable member and a 10 lever for actuating said movable member, and an adjuster slidably mounted on said carrier and carrying said clamp.

In testimony whereof, I set my hand, this
16th day of September, 1924.

THOMAS E. WINDLE.
